UNITED STATES PATENT OFFICE.

ELMER C. MORRIS, OF CHICAGO, ILLINOIS, ASSIGNEE, BY MESNE ASSIGNMENTS, TO SERVO-PAPER CORPORATION, A CORPORATION OF ILLINOIS.

FOLDED-SHEET OBJECT AND METHOD OF FORMING SAME.

Application filed March 3, 1924. Serial No. 696,492.

This invention relates to the preparation of a folded article for use in a dispensing cabinet and to the article itself, relating more especially to napkins, towels, toilet paper, and the like, the same being folded from paper of various qualities.

Among the objects of my invention are to produce an article of the character referred to which may be picked up in bundles or individually and placed in a dispensing cabinet without consideration as to which side is directed toward the dispensing opening or which end is up; and to produce an article which may be readily folded by machine and packed with other like objects in a pile without interlacing; to produce an article of the character stated which can be dispensed from a dispensing container without the necessity of being interlaced with other like articles; and such further objects, advantages and capabilities as will later more fully appear and as are inherent in the construction disclosed.

My invention further resides in the combination, construction, and arrangement of parts illustrated in the accompanying drawing, and, while I have shown therein a preferred form of my invention, I desire the same to be understood as illustrative only and not as limiting said invention.

In the drawing annexed hereto and forming a part hereof, Fig. 1 is a perspective view of an article to be folded, with dotted lines thereon to show where the folds are to be made; Fig. 2 is a perspective view of a folded article, the folded over portions of which have been partially unfolded; Fig. 3 is a perspective view of the same article in completely folded condition and in dotted lines a dispenser having an opening through which a corner of the article may be grasped and the article pulled out through the opening; Fig. 4 is a transverse section of the article as shown in Fig. 3.

Referring more in detail to the annexed drawing, numeral 1 designates the central body portion of an article in accordance with my invention, while 2 and 3 designate the opposite edge portions of this folded article, said edge portions being folded inwardly upon opposite sides of the central body portion 1, along the lines 4 and 5. These edge portions, in the preferred form of the invention, comprise diagonally opposite corner portions, which

are folded to provide an elongated intermediate or body portion. The folded corner portions are of considerable area so that they mutually overlap and overlie the middle part of the intermediate portion. They provide large triangular tabs respectively positioned on opposite faces of the intermediate portion and which are free at their apexes so that they can be readily grasped. The folding of the extensive corner portions form an elongated intermediate or body portion, at the ends of which the other two diagonally opposite corner portions remain unfolded to provide triangular or V-shaped extensions thereat.

In actual use of the old type of folded article, it has been found that attendants often get the articles into the dispensing container with the loose edge turned back away from the dispensing opening so that there is no opportunity to easily grasp the folded over edge of the article and withdraw it from the container. It is therefore my purpose to so fold such articles that, no matter how inattentive the attendant may be, the article cannot be put in incorrectly. With an article folded as shown in the attached drawing, whichever side is out or whichever end is up there will always be a free corner or edge which may be reached through the dispensing opening for the easy withdrawal of the article from the container. It will be observed by reference to the drawing that the folded over corners of the article overlap each other on the center of the body portion, the combined length of the folded over corners exceeding the width of the body portion. This is a very valuable feature of the invention as the overlapping corners reinforce the body portion, preventing the article from excess bending or collapsing when being dispensed under necessary tension through an opening in a dispensing cabinet. While the foremost article presents an outstanding corner by reason of a multiple of overlapping corners in the center of a quantity of articles when held in superposed relation and in dispensing position against marginal flanges adjacent a dispensing opening in a cabinet.

In folding two opposite corners of the article on diagonal lines a central body is formed with V-shaped ends. The V-shaped ends enable the use of a dispensing cabinet with a substantially large dispensing open-

ing, which is highly essential for successfully dispensing paper napkins. The V-shaped ends prevent excess bulging of the article when under pressure or when the 5 stack is exhausted to a comparatively few articles as the V-shaped ends are entirely confined by large marginal flanges at the ends of the dispensing opening in the cabinet. The edges of the folded corners being twice 10 the thickness of the V-shaped ends and obviously is the point of friction on the article, are held by extremely small flanges at the sides of the dispensing opening. Thus a slight movement of the side of the article, 15 by grasping a V-shaped corner, releases the article without resistance or inconvenience. While I have shown in my drawing a quarter folded paper napkin with two opposite corners folded over upon opposite sides 20 of the central body portion thereof, I desire it understood that the articles are not of a necessity in quarter folded shape before receiving the final fold, since a single sheet or a plurality of sheets may equally as well 25 be folded in the manner indicated.

While it is preferable to fold the tabs so that they are positioned on opposite faces of the intermediate part, as shown in the drawing, yet it is obvious that they can also 30 be folded to overlap each other on the same face of the intermediate part. In the claims in the use of "the folded corner portions in mutually overlapping relation and overlying the intermediate portion," or equivalent 35 statement, it is intended that this description be sufficiently comprehensive to include napkins in which the tabs are folded to overlie the opposite faces of the intermediate part and also napkins in which both tabs 40 overlap the same face of the intermediate portion.

Having now described my invention, I claim:

1. As an element of a package to be dispensed through an opening in a dispensing cabinet, a paper napkin first folded in a rectangular form and then two diagonally opposite corner portions folded to form an elongated intermediate portion, with the 45 folded corner portions in mutually overlapping relation and overlying the intermediate portion to provide free triangular tabs on the middle part of the intermediate portion.

2. As an element of a package to be dis-

pensed through an opening in a dispensing cabinet, a paper napkin first folded in a rectangular form and then two diagonally opposite corner portions folded to form an elongated intermediate portion, with the 60 folded corner portions in mutually overlapping relation and respectively overlying the opposite faces of the intermediate portion to provide free triangular tabs on the middle part of the intermediate portion. 65

3. As an element of a package to be dispensed through an opening in a dispensing cabinet, a paper napkin successively folded on two normally intersecting lines to provide a rectangular form having a multiplicity of plies, said rectangular form then having two opposite corners folded on diagonal lines to form a central body portion having substantially uniform V-shaped ends and V-shaped corner portions, the combined length 70 of the V-shaped corner portions exceeding the width of the body portion. 75

4. As an element of a package to be dispensed through an opening in a dispensing cabinet, a paper napkin successively folded on two normally intersecting lines to provide a rectangular form having a multiplicity of plies, said rectangular form then having two opposite corners folded in opposite directions on diagonal lines to form a central body portion having substantially uniform V-shaped ends and a V-shaped corner portion on each face of the central body portion, the combined length of the corner portions 80 exceeding the width of the body portion. 85

5. As an element of a package to be dispensed through an opening in a dispensing cabinet, a paper napkin first folded in a rectangular form and then two diagonally opposite corner parts folded along approximately parallel diagonal lines to form an elongated intermediate portion having opposite triangular ends substantially uniform as to shape and size, said folded-over corner parts being in overlapping relation and overlying the intermediate portion to provide free triangular tabs of uniform shape and size and having their loose corners positioned about midway of the longitudinal dimension of the elongated intermediate portion. 90 95 100 105

In witness whereof, I hereunto subscribe my name to this specification.

ELMER C. MORRIS.
